UNITED STATES PATENT OFFICE.

FRANK W. BAUM, OF SPRINGFIELD, MASSACHUSETTS, ASSIGNOR TO THE F. WESEL MANUFACTURING COMPANY, OF NEW YORK, N. Y.

MAKE-READY PRESS.

SPECIFICATION forming part of Letters Patent No. 609,650, dated August 23, 1898.

Application filed November 6, 1897. Serial No. 657,660. (No model.)

To all whom it may concern:

Be it known that I, FRANK W. BAUM, a citizen of the United States, residing at Springfield, in the county of Hampden and State of Massachusetts, have invented certain new and useful Improvements in Make-Ready Presses, of which the following is a specification.

This invention relates to an improved make-ready press, and is used for making the faces of electrotype-plates perfectly flat, and therefore scarcely any make-ready is necessary, so that printing establishments having an electrotype department can use the improved press at a considerable saving of time and labor; and the invention consists of a make-ready press for electrotypes comprising a tilting table, on which the electrotype is placed face downward, a cover provided with a hurdy-gurdy plate—namely, a plate having a number of projecting teats on its exposed surface—means for pressing the cover tightly on the electrotype-plate, so as to render the same perfectly flat, and means for holding the tilting table and cover in horizontal position and for releasing them, so as to tilt them into upright position for supplying them with cold water for cooling the electrotype-plate.

In the accompanying drawings, Figure 1 represents a perspective view of my improved make-ready press for electrotypes. Fig. 2 is a vertical longitudinal section showing the parts of the table in position for flattening the electrotype-plate. Fig. 3 is a vertical longitudinal section of the same, showing the table and cover in position for receiving the cooling-water; and Fig. 4, an enlarged view in section of a portion of the press.

Similar letters of reference indicate corresponding parts.

Referring to the drawings, the supporting-frame of my improved make-ready press for electrotypes consists of two upright standards A, which are connected by transverse rods. In fork-bearings a at the upper part of the side standards A are supported the trunnions b of a tilting table B, said trunnions being so arranged as to be slightly in front of the transverse center line of the table, so that the table when not supported

at the rear part will tilt into vertical position. The side standards A support at their front part a transverse rod A', which is provided with an upright stop-pin b', that supports the front part of the table A when the same is 55 in horizontal position. The rear part of the table A is provided with lugs d, which are slotted to receive adjustable bearing-pieces d', set in position by means of screws d², so that while the pivot-shaft d³, which extends 60 through lugs d⁴ of the cover D, can turn in its bearings it has a slight play therein. The cover D is provided at opposite sides with handles h, and both the cover and the table are formed with beveled or flaring lips 65 d⁵ b², respectively, to provide a pouring-mouth when the table and cover are in the position shown in Fig. 3.

The table is provided at opposite sides with uprights B' B². To the upper end of the 70 upright B² is pivoted a cross-head E, which is provided at the center with an interiorly-threaded sleeve for a screw-spindle E', having a hand-wheel E², and at its opposite or free end with a hook-shaped portion e, that 75 engages the upper reduced end of the upright B' when it is swung in position across the table, as shown in Fig. 2. In the rear part of the supporting-frame is journaled a transverse rod f, which carries an upwardly-extending arm F, recessed at its upper end, and which engages and supports the rear end of the tilting table B when in position as 80 shown in Fig. 2. To the rod f is further applied a hand-lever F', which rests normally on 85 a pin f' at the front part of the side standard A.

The cover D is provided at its hinged end with a stop-pin f², which abuts against the upper end of the lever F, so as to hold the 90 cover in upright and slightly-inclined position, as shown in Fig. 1, and prevent it from tilting beyond this position. The cover D is provided with a hurdy-gurdy plate D', which fits into a recess of the cover and which is 95 cushioned by rubber packing D², interposed between the hurdy-gurdy plate and the cover. The hurdy-gurdy plate is of the well-known construction and is preferably composed of copper, having a number of projecting teats, 100

leveled off carefully, so that a uniform pressure in the same plane is exerted on the electrotype to be flattened in the press.

My improved make-ready press is operated 5 as follows: The electrotype-plate after being pressed on the planing or roughing machine is first heated on a gas-heated table such as is used in all electrotyping establishments and then placed face downward on the top 10 of the tilting table B, which is then supported in horizontal position, as shown in Fig. 1, and the cover in upright position. The cross-head E is detached from the upright B' and swung alongside of the table, as shown in Fig. 1. 15 The cover D is then swung in downward direction onto the electrotype-plate, the cross-head moved over so as to connect with the upright B', after which the screw-spindle E' is turned by the hand-wheel and the cover 20 and the hurdy-gurdy plate in the same firmly pressed onto the electrotype-plate, so that the latter is made perfectly flat by the pressure to which it is subjected by the hurdy-gurdy plate on the table. The heated electrotype- 25 plate is subjected to a gentle pressure for a few seconds, after which the cross-head E is swung back and the lever F' is raised, so that the arm F is released from the rear part of the table, when the same, with its cover, tilts 30 slowly into vertical position, as shown in Fig. 3, the tilting being controlled by the handles h, attached to the cover. When the table, with its cover, is in upright position, cold water is poured through mouth d⁵ b² into the 35 space between the table and cover, so that the water passes through the small channels between the teats in the hurdy-gurdy plate and cools the electrotype-plate, so that it can be removed. This cooling-water is collected in 40 a drip-pan C, which surrounds the lower part of the supporting-frame of the make-ready press, and is removed from same from time to

time. The cooling of the plate gives the metal a "set" and prevents any springing of the plate when the pressure is released. When 45 small electrotype-plates are subjected to pressure, it is unnecessary to use any water for cooling them, as they cool quick enough by the action of the air. The operation of making the electrotype-plate ready in the press 50 takes less than a minute, after which the completed plates are taken out of the press, dried, and are finally shaved off at the back by a shaving-machine to the required thickness.

My improved make-ready press forms a 55 ready and convenient press for conveniently flattening electrotype-plates in getting ready for printing, so as to dispense with the time-consuming make-ready of the plates heretofore required.

Having thus described my invention, I claim as new and desire to secure by Letters Patent—

The combination of a table, a cover hinged to said table, a hurdy-gurdy plate fixed to 65 the inner face of the cover and provided with a multiplicity of teats on its exposed face, means for pressing the cover toward the table whereby the teats on the hurdy-gurdy plate are pressed against the electroplate, and 70 means for sustaining the table, cover, and hurdy-gurdy plate and electroplate in upright position, so that cooling-water can be caused to flow downwardly between the teats of the hurdy-gurdy plate and along the adjacent 75 surface of the electroplate, substantially as set forth.

In testimony that I claim the foregoing as my invention I have signed my name in presence of two subscribing witnesses.

FRANK W. BAUM.
